PLIERS

Alexander Cruickshank, Clayburn, British Columbia, Canada

Application December 13, 1937, Serial No. 179,419

2 Claims. (Cl. 81—44)

My invention relates to improvements in pliers of the adjustable type, the objects of which are to provide means for securing the pivot pin connecting the plier jaws in adjusted position by applying closing pressure upon the plier handles, and to provide means whereby the pliers can be adjusted for jaw opening by exerting thumb pressure upon one part when holding the plier handles in one hand. The invention consists essentially 5 of a plier having jaws and handles, which jaws are pivotally connected by a pin held in one jaw and engaging one of a plurality of notches formed in a slotted portion of the opposite jaw, said pin being connected by pairs of links extending from 10 one of the handles, as will be more fully described in the following specification and shown in the accompanying drawing, in which:

Fig. 1 is a general view of the pliers closed, with the bar link in section.

Fig. 2 is a general view of the pliers in extended position.

In the drawing like characters of reference indicate corresponding parts in each figure.

The numeral 1 indicates a handle which is 25 formed integrally with a jaw 2 and an inwardly projecting lug 3. The lug is provided with a slot 4 having a plurality of notches 5 on its lower side, each of which is adapted to selectively receive a pivot pin 6 extending through the lug 7 of a jaw 30 8. The lower extremity of the jaw 8 is pivotally connected by a pin 9 to a second handle 10. Secured to opposite ends of the pivot pin 6 is a bar link 11 formed with two side members 12 connected together intermediate their length with a 35 bar 13, which, when squeezing pressure is applied to the handles 1 and 10 is adapted to bear upon the underside of the lug 3.

The lower end of the bar link 11 is connected to the handle 10 by a link 14 which is pivoted at its 40 outer end to the handle 10 by a pin 15 and is pivoted at its inner end to the bar link 11 by a pin 16.

As a means of ensuring engagement between the underside of the jaw lug 3 and the bar 13, I 45 may use a light spring 17, see Figure 1, anchored to each of the links 11 and 14, which will tend to swing the lower end of the bar link 11 towards the handle 1.

In use, the tool is set to engage a nut or other article to be gripped by holding both handles 1 and 10 with one hand, if desired and thumb pres-

sure in an upward direction is applied to the intersection of the links 11 and 14, which releases the pin 6 from its set position in one of the notches 5 of the slot 4, thus allowing the lug 3 to be moved freely in or out until the desired jaw opening is attained. When this is done it suffices to apply the jaws 2 and 8 to the article to be turned or gripped and to squeeze the handles 1 and 10 together. The force applied to the handles after the jaws have closed upon the article to be gripped, forces the bar 13 into firm contact with the underside of the lug 3, thus locking the pivot pin 6 in place in its notch 5 and transfers the fulcrum between the handles to the pin 16, the link 14 and the pin 15. Final squeezing pressure 15 of the handles will cause the jaw 8 to rock inwardly on the pin 6 in response to outward thrust at the pin 9 from the movement of the upper end of the handle 10.

What I claim as my invention is:

1. A plier comprising a pair of jaws and a pair of handles, one of said jaws being formed integrally with one handle and the second jaw being hingedly connected with the second handle, a lug extending inwardly from each jaw, one lug having a slot provided with notches and the second jaw having a pin passing through said slot and adapted to rest in any of said notches, a bar link connected at one end to the pin and a link connected to the hingedly connected handle and to the bar link, said bar link having a transverse bar adapted to engage the underside of the slotted lug when closing force is applied to the handles.

2. A plier comprising a pair of jaws and a pair of handles, one of said jaws being formed integrally with one handle and the second jaw being hingedly connected with the second handle, a lug extending inwardly from each jaw, one lug having a slot provided with notches and the second jaw having a pin passing through said slot and adapted to rest in any of said notches, a bar link connected at one end to the pin and a link connected to the hingedly connected handle and to the bar link, said bar link having a transverse bar adapted to engage the underside of the slotted lug when closing force is applied to the handles, and spring means for urging the bar of the bar link into engaging position with the underside of the slotted lug.

ALEXANDER CRUICKSHANK. 50
